(57) **CLAIM**

The ornamental design for an electronic vaporizer, as shown and described.

DESCRIPTION

FIG. 1 is a front elevational view of an electronic vaporizer showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, top and right side perspective view thereof;

FIG. 8 is a rear, bottom and left side perspective view thereof; and,

FIG. 9 is an enlarged view of portion 9 in FIG. 7.

The broken lines in the drawings illustrate portions of the electronic vaporizer which form no part of the claimed design.

The dot-dot-dash broken lines shown in FIGS. 7 and 9 surrounding the detail views are for annotating the enlargements and form no part thereof.
